[57] CLAIM

The ornamental design for a furniture base, as shown and described.

DESCRIPTION

FIG. 1 is a perspective view of a furniture base, showing my new design, the broken lines being for environmental purposes only and forming no part of the claimed design;

FIG. 2 is a top plan view;

FIG. 3 is a side elevational view; and,

FIG. 4 is a bottom plan view thereof.

FIG.1

FIG.3

FIG.2

FIG.4
